UNITED STATES PATENT OFFICE.

HENRY W. LAMB, OF BIRMINGHAM, ALABAMA, ASSIGNOR TO CENTURY MOP CORPORATION, OF NEW YORK, N. Y., A CORPORATION OF NEW YORK.

COMBINED MOP AND WRINGER.

Application filed March 30, 1923. Serial No. 628,699.

To all whom it may concern:

Be it known that I, HENRY W. LAMB, a citizen of the United States of America, residing at Birmingham, in the county of Jefferson and State of Alabama, have invented certain new and useful Improvements in Combined Mops and Wringers, of which the following is a specification.

My invention relates to an improved type 10 of mop which is characterized by the provision of very simple, effective and inexpensive means for holding, wringing, drying and changing of the mop.

My invention relates to that class of mop 15 which makes use of a cloth as the mopping element as contrasted with those formed of strings or the like which are permanently mounted on the mop head.

According to my invention the mop cloth 20 has its ends detachably connected to separable holder elements on the handle, one of the elements being stationary and the other slidably on the handle so that the mop cloth can be stretched and wrung out by twisting 25 it about the handle. Such arrangement lends itself readily to the drying of the mop by inverting the handle, as then the slidable holder element will drop down and stretch the cloth to its full length, and the mop can 30 be stood against the wall with the cloth in this position without probability of the latter damaging or soiling the wall.

My preferred means for detachably securing the ends of a mop cloth in the holder elements is by forming a seam or enlargement 35 across the ends of the cloth and providing notches in the flattened loops of the holder elements so that the cloth can be threaded in through these notches and thus easily assembled or removed while being at all times effectively held while in use by the holder elements. The advantage of this arrangement is that the holder elements require no clamp means to hold the cloth and the cloth 40 as a whole can be readily removed, cleaned and replaced, thus making the mop very sanitary.

A further object of my invention is to perfect the design of the mop holder elements 45 and to provide one with means for its de-

tachable connection to the mop handle and the other with a sleeve adapted to slide over the mop handle and to interlock with the other holder element so as to prevent relative turning or twisting of the holder elements while the mop is in use. 55

My invention also contemplates an improvement in the mop cloth itself in that I prefer to have the main body portion of the cloth relatively wider than its ends toward which it tapers. This enables me to use narrowed seamed ends to engage and fit in the holder elements which are of like width with such narrowed ends. 60

My invention also comprises the novel details of construction and arrangements of parts which in their preferred embodiment only are illustrated in the accompanying drawings, which form a part of this specification, and in which:— 65

Fig. 1 illustrates the mop in side elevation as it appears in service with its handle partly broken away.

Fig. 2 is a perspective view of the mop showing the cloth stretched its full length 75 preparatory to being wrung or dried.

Fig. 3 shows the cloth being partially wrung, which is desirable for certain uses of the mop.

Fig. 4 shows a mop cloth being wrung 80 dry.

Fig. 5 is a perspective view of the mop parts detached in relative position for assembling, the mop cloth being omitted.

Figs. 6 and 7 are enlarged side elevation 85 and longitudinal cross-sectional views respectively of the mop head.

Fig. 8 is a perspective view of my preferred mop cloth.

Similar reference numerals refer to similar parts throughout the drawings.

In the preferred embodiment of my invention which is illustrated in the drawings, the mop is shown comprising a handle 1 having its lower end tapered and threaded at 2 and adapted to be screwed into a tapered threaded socket 3 which has rigid thereon a mop holding loop 4 which projects at right angles to the mop handle for a substantial distance on each side and is flattened to form a long, 95 100

narrow, transverse opening or slot 5 which receives the mop cloth. Preferably the loop 4 is interrupted at 6 forming a neck or opening through which the mop cloth 7 can be threaded when securing it in or detaching it from the holder loop. Across each end of the mop cloth I provide a seam, bead or enlargement 8 of such size that it cannot be pulled through the holder slot 5.

10 The handle is adapted to slip freely through a metal sleeve 9 which is also adapted to slip down over the socket 3. This sleeve 9 has rigidly mounted thereon at one side a second flattened loop holder 10 for the 15 mop cloth which is similar to the holder 4 and of the same size but is offset laterally therefrom sufficiently to miss the socket 3 and allow the sleeve 9 to be drawn up on the handle, as indicated in Fig. 2. The sleeve 9 is also preferably provided with longitudinal raised grip shoulders 11 and it is elongated sufficiently to enable it to be grasped in the hand for the purposes later described. The sleeve 9 at its lower end and on the 20 opposite side from the holder loop 10 is provided with opposed aligning notches 12 which are adapted to fit down over the holder 4 when the mop parts are assembled in operating position, as shown in Fig. 6. This will 25 interlock the sleeve and socket and prevent rotation or relative movement of the holders 4 and 10 about the handle.

30 The mop cloth in its preferred form is shown in Fig. 7 and has a body portion of the desired width while its ends are tapered towards the seam or bead 8 so that it is not necessary to make the holder loops 4 and 10 as wide as the widest portion of the mop cloth. This arrangement however is optional and it is to be understood that the un-tapered mop cloths may be used and also if desired the mop cloth may be formed as a 35 loop with the ends connected.

40 In operation, the sleeve 9 is first slipped over the lower end of the handle and the latter is then screwed into the socket 3. The seamed ends of the cloth are woven or threaded through the opening 6 in each of the holder loops 4 and 10 with the seams 8 45 interturned, as illustrated in Fig. 7, and then the sleeve 9 is allowed to drop down over the socket 3 and interlock with the holder loop 4. The mop is now ready for use as illustrated in Fig. 1. If it is desired to partially 50 wring the mop it should be drawn out to the position shown in Fig. 2, and then the sleeve 55 9 grasped and twisted once or twice about the handle so as to wind the upper end of the mop cloth tightly about the handle and 60 wring it, as shown in Fig. 3, while leaving the lower end of the mop cloth unwrung. If, however, it is desired to effectively 65 wring the entire mop cloth, then the handle 9 is slipped lower down on the handle and twisted about the handle until the mop cloth

is wound tightly about the handle, as shown in Fig. 4, which will wring it dry. If it is desired to dry the cloth, the mop is inverted and the cloth thereupon takes the position shown in Fig. 2, in which it will readily dry, and it is to be observed that it can be leaned against the wall and will not tend to soil the wall while it is being dried. The cloth can be readily removed from the holder loops by pushing it to one side in the loop 4 or 10 until one side edge of the seamed end of the mop cloth can be passed out through the notch and then the cloth can be pulled out of the holder and thoroughly washed or laundered, thus making the mop very sanitary.

Having thus described my invention, what I claim as new and desire to secure by Letters Patent, is:—

1. A combined mop and wringer comprising a handle having its outer end threaded, a wide flattened loop having a socket adapted to screw onto the threaded end of said handle, a sleeve freely slideable over and rotatable around the handle and socket and having rigid thereon a second wide flattened loop, said loops being juxtaposed in parallel relation when the sleeve overlaps said socket, means to hold the loops against relative rotation when in mopping position, and a flat mop cloth connected at its ends to said loops. 90

2. A combined mop and wringer comprising a solid handle, a socket member secured to the outer end thereof and having a flat loop connected thereto, a sleeve freely slideable and rotatable on the handle above the socket member, said sleeve having notches and an off set mop attaching loop, said notches adapted to receive the loop on the socket member to lock the loops when in juxtaposed parallel relation against relative rotation, and a flat mop fabric having its terminal ends secured to said loops. 100

3. A combined mop and wringer, comprising a handle having mounted thereon two mop attaching loops one mounted rigidly on the outer end of the handle and the other mounted slideable and rotatable on the handle above the first, a flat mop cloth having its terminal ends connected to said loops, and means fixedly supported relatively to one of said loops for interlocking with the other loop when in operative mopping position for preventing relative rotation of the loops, said mop cloth adapted to be twisted spirally around the handle for wringing when the interlocking means is inoperative. 110

4. A combined mop and wringer comprising a rigid handle having a hand gripping portion and a mop wringing portion, a wide flattened loop connected to the handle at the outer end of the wringing portion, a sleeve slideably and rotatably mounted on the wringing portion of said handle and carrying a second wide flattened loop, said loops when arranged in operative mopping asso- 120 125 130

ciation being juxtaposed in parallel relation at the outer end of the handle entirely removed from the hand gripping portion of said handle, means on said sleeve for engaging with the first mentioned loop for holding said loop when in mopping position against relative rotation, and a mop cloth having its terminal ends secured to said

loops and adapted to be twisted around the handle in spiral form for wringing wholly 10 within the zone of movement of the sleeve by relative rotation of the sleeve with respect to the handle.

In testimony whereof I affix my signature.

HENRY W. LAMB.
